US00D991253S

(12) **United States Design Patent** (10) **Patent No.:** **US D991,253 S**
Wang (45) **Date of Patent:** **** Jul. 4, 2023**

(54) **ROUTER**

(71) Applicant: **Quanta Computer Inc.**, Taoyuan City (TW)
(72) Inventor: **Te-Chieh Wang**, Taoyuan City (TW)
(73) Assignee: **QUANTA COMPUTER INC.**, Taoyuan (TW)

(**) Term: **15 Years**

(21) Appl. No.: **29/723,682**

(22) Filed: **Feb. 10, 2020**

(30) **Foreign Application Priority Data**

Nov. 26, 2019 (TW) 108307206

(51) **LOC (14) Cl.** **14-02**
(52) **U.S. Cl.**

(57) **CLAIM**

The ornamental design for a router as shown and described.

DESCRIPTION

FIG. 1 is a front perspective view of a router, which can forward data packets between computer networks, in accordance with our new and ornamental design;

FIG. 2 is a front view thereof;

FIG. 3 is a rear view thereof;

FIG. 4 is a left side view thereof;

FIG. 5 is a right side view thereof;

FIG. 6 is a top plan view thereof;

FIG. 7 is a bottom plan view thereof;

FIG. 8 is a rear perspective view thereof;

The broken lines shown in FIGS. 1, 3, 5, 6, and 8 illustrate portions of the router that form no part of the claimed design.

1 Claim, 8 Drawing Sheets
